UNITED STATES PATENT OFFICE

112,119

DESIGN FOR A PRINTING TELEGRAPH APPARATUS COVER

George R. Lum, New York, N. Y., and Alfred L. Mell, Chicago, Ill.; said Lum assignor to Bell Telephone Laboratories, Incorporated, New York, N. Y., a corporation of New York, and said Mell assignor to Teletype Corporation, Chicago, Ill., a corporation of Delaware

Application March 12, 1938, Serial No. 75,784

Term of patent 14 years

To all whom it may concern:

Be it known that we, George R. Lum and Alfred L. Mell, citizens of the United States, residing at New York, in the county of New York and State of New York, and at Chicago, in the county of Cook and State of Illinois, respectively, have invented a new, original, and ornamental Design for Printing Telegraph Apparatus Cover, of which the following is a specification, reference being had to the accompanying drawings forming a part thereof.

Fig. 1 is a perspective view of the printing telegraph apparatus cover taken at one corner thereof;

Fig. 2 is a perspective view taken at the rear thereof;

Fig. 3 is a perspective view taken at one end thereof; and

Fig. 4 is a perspective view taken at the front thereof.

What is claimed is:

The ornamental design for a printing telegraph apparatus cover, substantially as shown.

GEORGE R. LUM.
ALFRED L. MELL.
